UNITED STATES PATENT OFFICE.

GABRIEL UPTON, OF PHILADELPHIA, PENNSYLVANIA, ASSIGNOR TO CONYERS BUTTON AND THEODORE A. FLEU, BOTH OF SAME PLACE.

DESIGN FOR KNITTED FABRIC AND FRINGE.

SPECIFICATION forming part of Design No. 12,267, dated May 17, 1881.

Application filed May 31, 1879. Term of patent 3½ years.

To all whom it may concern:

Be it known that I, GABRIEL UPTON, of Philadelphia, Pennsylvania, have produced or invented a new and original Design for a Knitted Fabric and Fringe, of which the following is a specification.

My design for a knitted fabric is fully shown in the accompanying photographic illustration.

The body of the fabric consists of fine vertical cords *a* and lateral threads *b*, forming a background for holding and displaying the short projecting plumes *d*, which constitute the prominent characteristic of the design. Each of the plumes *d* consists of a single thick thread projecting from the background, to which it is secured, and it is in this respect that my design differs materially from an ordinary tufted fabric in which each tuft is composed of a number of fine threads.

The fabric has a fringe consisting, essentially, of projecting plumes *f*, suspending-threads *b*, and cords *m*, and between the body of the fabric and the fringe is a heading consisting

of plain looped threads of a character too fully shown to need description. This fringe and heading, however, form no part of the design.

In my Patent No. 11,274, July 1, 1879, application for which was filed simultaneously herewith, I have shown and described a fabric the body of which is similar in general appearance to that of my present fabric; but this feature separately considered was not claimed in said patent.

Irrespective of the colors employed, I claim—

The design for a knitted fabric, said design comprising the vertical cords *a*, the lateral threads *b*, and the projecting plumes *d*, all substantially as described, and as shown in and by the accompanying drawing.

In testimony whereof I have signed my name to this specification in the presence of two subscribing witnesses.

GABRIEL UPTON.
